US0D1066900S

(12) **United States Design Patent** (10) Patent No.: **US D1,066,900 S**
(45) Date of Patent: ** Mar. 18, 2025

(54) **SOCK**

(71) Applicant: **TBL Licensing LLC**, Stratham, NH (US)

(72) Inventors: **Sue Jesch**, Denver, CO (US); **Anne Wiper**, Boulder, CO (US); **John Ramsey**, Denver, CO (US); **Laura Marano-Heins**, Lafayette, CO (US)

(73) Assignee: **TBL LICENSING LLC**, Stratham, NH (US)

(**) Term: **15 Years**

(21) Appl. No.: **29/907,120**

(22) Filed: **Jan. 4, 2024**

(57) **CLAIM**

The ornamental design for a sock, as shown and described.

DESCRIPTION

FIG. 1 is a three-dimensional back view of a sock in accordance with a first embodiment of our design;

FIG. 2 is a side view thereof;

FIG. 3 is a two-dimensional back view in a first configuration in accordance with the first embodiment;

FIG. 4 is a two-dimensional back view in a second configuration in accordance with the first embodiment;

FIG. 5 is a two-dimensional side view in accordance with the first embodiment;

FIG. 6 is a three-dimensional back view of a sock in accordance with a second embodiment of our design;

FIG. 7 is a side view thereof;

FIG. 8 is a two-dimensional back view in a first configuration in accordance with the second embodiment;

FIG. 9 is a two-dimensional back view in a second configuration in accordance with the second embodiment;

FIG. 10 is a two-dimensional side view in accordance with the second embodiment;

FIG. 11 is a three-dimensional back view of a sock in accordance with a third embodiment of our design;

FIG. 12 is a side view thereof;

FIG. 13 is a two-dimensional back view in a first configuration in accordance with the third embodiment;

FIG. 14 is a two-dimensional back view in a second configuration in accordance with the third embodiment;

FIG. 15 is a two-dimensional side view in accordance with the third embodiment;

FIG. 16 is a three-dimensional back view of a sock in accordance with a fourth embodiment of our design;

FIG. 17 is a side view thereof;

FIG. 18 is a two-dimensional back view in a first configuration in accordance with the fourth embodiment;

FIG. 19 is a two-dimensional back view in a second configuration in accordance with the fourth embodiment;

FIG. 20 is a two-dimensional side view in accordance with the fourth embodiment;

FIG. 21 is a three-dimensional back view of a sock in accordance with a fifth embodiment of our design;

FIG. 22 is a side view thereof;

FIG. 23 is a two-dimensional back view in a first configuration in accordance with the fifth embodiment;

FIG. 24 is a two-dimensional back view in a second configuration in accordance with the fifth embodiment;

FIG. 25 is a two-dimensional side view in accordance with the fifth embodiment;

FIG. 26 is a three-dimensional back view of a sock in accordance with a sixth embodiment of our design;

FIG. 27 is a side view thereof;

FIG. 28 is a two-dimensional back view in a first configuration in accordance with the sixth embodiment;

FIG. 29 is a two-dimensional back view in a second configuration in accordance with the sixth embodiment; and,

FIG. 30 is a two-dimensional side view in accordance with the sixth embodiment.

The broken lines show portions of the sock that form no part of the claimed design.

While the side view(s) of each embodiment shows one side of the sock, in additional claimed embodiments the opposite side of the sock is a mirror image thereto.

The areas of contrasting appearance may be associated with different colors, different materials or combinations of materials, different stitching or other sock property.
